CYLINDER HEAD FOR INTERNAL COMBUSTION ENGINES

Chester Arthur Gants and Daniel Arthur Gants,
Abilene, Kans.

Application February 18, 1938, Serial No. 191,322

3 Claims. (Cl. 123—173)

This invention relates to a cylinder head unit for internal combustion engines and more particularly to a cylinder head in which the usual sparking plugs are dispensed with.

5 The principal object of the invention is to provide a cylinder head in which the spaced sparking electrodes for igniting the combustion mixture in the cylinder are formed as an integral part of the cylinder head to thus eliminate inherent 10 disadvantages of the conventional sparking plug.

A further object of the invention is to incorporate the high tension spark gap interiorly of the combustion chamber so that the electrodes may be of much sturdier construction than is customary 15 and to provide integral conduits in the cylinder head within which the electrical conductors to the spark gaps are contained to obtain a clean engine top without the usual array of ignition wires.

A still further object of the invention is to 20 so position the spark gaps that they are readily accessible for replacement and adjustment.

In the drawing:

Fig. 1 is a horizontal cross sectional view of a cylinder head unit taken on line 2—2 of Fig. 2;

25 Fig. 2 is a vertical cross section of the cylinder head, showing the position of the electrodes and conductor conduit and the position of the cylinder head on the engine block;

Fig. 3 is a partial top plan of the cylinder head 30 unit, showing the detachable combustion chamber closure plates.

More specifically in the drawing, numeral 1 denotes a cylinder head unit, which, while illustrated as a four cylinder engine head, may include 35 any number of cylinders desirable. The general arrangement of the cylinder head is conventional, in that it is of unit construction and contains the customary cooling fluid passages 3 along the sides of the head and around the combustion chambers 4. The cylinder head unit is adapted to be bolted 40 directly to an engine cylinder block 5, and the entire unit may be readily substituted for heads now in use.

As seen from the drawing, integral internally 45 screw threaded bosses or projections 6 are cast or otherwise formed in each chamber 4 when the head is constructed and these bosses 6 extend transversely from the wall of the combustion chamber into the mid-section thereof. In the opposite side of the head unit a longitudinal tube 7 runs the full length of the cylinder block and connects with a plurality of transverse passages 8 communicating with the cylinder chambers 4. The outlet passages 8 are positioned directly 50 opposite the bosses 6, and the outer openings of

the passages are adapted to retain therein insulating tubes or sleeves 9. The insulating material forming the tubes or sleeves 9 may be of any desired material, such as heat resisting glass, quartz, porcelain or the like.

5 Adjustable screw threaded electrodes 10, having lock nuts 11 threaded thereon, are positioned in each of the bosses 6 with their outer ends terminating in approximately the center of the circumference of the combustion chambers 4. The electrodes 12 are retained in each of the insulating tubes 9 with the ends of the electrodes terminating a slight distance from the electrodes 10 to form a suitable spark gap therebetween. The electrodes 10 are screw threaded directly into the 15 bosses 6 and form a part of the cylinder head and engine construction and are grounded thereto, while the electrodes 12 are insulated from the head or engine by means of the tube 9. The electrodes may be fabricated from any well known 20 heat resistant alloys which possess the necessary conductivity and stamina for such use.

A series of insulated high tension wires 13 are connected to the outer ends of each of the electrodes 12, and, as seen in Fig. 1, this series of 25 electrical conductors are carried through the longitudinal tube 7, which communicates with the passageways 8. A suitable disc 14 is preferably fitted into the outer end of the tube 7 so that the tube is completely sealed off from dirt, water 30 and the like. The series of conductors 13 are run from the disc into a unitary cable 15 and thence to the distributor or other electrical make and break device with which the engine is provided.

While the combustion chambers 4 may be 35 formed with integral top portions, it has been found desirable to close off the tops of each of the individual combustion chambers 4 by means of bolted and gasketed plate 16, having a screw threaded plug 17 therein for testing the compression of the individual cylinder. When replacement or adjustment of the electrodes is necessary, it is a comparatively simple matter to remove the bolts holding the plates 16 to give full 40 access to the interior of the cylinder.

45 It will be understood by those skilled in the art that this invention provides a simple and rugged sparking arrangement for internal combustion engines wherein the electrodes per se may be of much heavier construction than is possible with the customary sparking plugs and furthermore, that by reason of their horizontal position within the combustion chambers the 50 sparking takes place in approximately the center thereof which insures rapid propagation of 55

the combustion flame. This also lessens carbonizing of the points and prevents oil condensation.

The invention also permits a much cleaner external appearance of the engine and insures 5 that the high tension wires are completely inclosed to thus prevent deterioration, exposure to accident, and complete absence of absorption of moisture.

Because of the considerably increased size of 10 the electrodes over customary plugs, they remain efficient over long periods of operation, and when adjustment or replacement is necessary, the electrodes are readily accessible.

While our invention has been shown in connection with a fluid cooled engine, it is to be 15 understood that this is for the purpose of illustration only and that the invention is equally applicable to engines that have solid heads and those which are air-cooled.

20 What we claim is:

1. In an internal combustion engine, a removable cylinder head therefor, said head having longitudinal water circulating passages therein, transverse bosses integrally secured to the wall 25 of one of said passages and extending into the top of the cylinder chambers, electrodes secured in said bosses, spaced electrodes secured to the opposite circulating wall, said electrodes being insulated therefrom, a conduit formed integrally with said wall lying at a right angle to said insulated electrodes and electrical conductors secured to each of said insulated electrodes positioned in said conduit, and extending beyond to 30 the end of said head.
- 35 2. An internal combustion engine including a removable cylinder head, a plurality of cham-

bers formed in said head corresponding to and directly above the bores of the cylinder of the engine to which the head is applied, a pair of oppositely extending electrodes secured to opposite sides of the chambers, a gap between the electrodes, one of said electrodes being threaded into the wall of the chamber, while the opposite spaced electrode is supported by but electrically insulated from the chamber, a longitudinal passage formed in said head and lying in spaced 10 relation to the series of insulated electrodes and insulated electrical conduits leading from the insulated electrodes through the longitudinal passage to outside the head.

3. In an internal combustion engine, a cylinder head therefor, said head comprising a unit 15 having vertical passages extending therethrough, cooling medium conduits extending around the passages and sides of the said head, a longitudinal tube formed in one side of said head and 20 lying within one of said cooling medium conduits, a plurality of spaced apart offset passages communicating with said tube and extending into the vertical passages, electrodes mounted in insulators secured in each of said offset passages, electrical conductors connected to each electrode, the conduits extending into and through the offset passages and longitudinal tube and complementary electrodes secured in spaced relation to the insulated electrodes, said 25 complementary electrodes being secured to and electrically grounded to the opposite walls of the vertical chambers.

CHESTER ARTHUR GANTS. 35
